Term of patent 7 years

(Cl. D7—7)

Fig. 1

Fig. 2

Fig. 1 is a front perspective view of a shoe or similar article, showing my new design.

Fig. 2 is a rear perspective view thereof.

The opposite side of the shoe is substantially the same as that shown in Fig. 1.

The dominant feature of my design resides in the portions shown in solid lines.

I claim:

The ornamental design for a shoe or similar article, substantially as shown and described.
